UNITED STATES PATENT OFFICE.

DANIEL T. FRIDENA AND WILLIAM E. JUDD, OF BROCKWAYVILLE, PENNSYLVANIA.

HAIR CURLER.

Application filed June 6, 1924. Serial No. 718,335.

To all whom it may concern:

Be it known that we, DANIEL T. FRIDENA and WILLIAM E. JUDD, citizens of the United States, residing at Brockwayville, in the 5 county of Jefferson and State of Pennsylvania, have invented a new and useful Hair Curler, of which the following is a specification.

This invention relates to hair curlers and 10 more particularly to a device especially designed for permanently waving the hair.

The primary object of the invention is to provide a device for permanently waving, the structure being such as to insure against 15 burning of the hair while in use.

Another object of the invention is to provide a device of this character wherein the hair will not touch the heated iron, but will be suspended in a heated compartment 20 while wrapped on a suitable curling iron.

A still further object of the invention is to provide a device of this character which may be conveniently handled without fear of the operator's hands being burned, by 25 the device.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a device constructed in accordance 40 with the invention.

Figure 2 is a sectional view taken on line 2-2 of Figure 1.

Figure 3 is a sectional view taken on line 3-3 of Figure 1.

Figure 4 is a sectional view taken on line 4-4 of Figure 1.

Figure 5 is an elevational view of the device.

Figure 6 is an end elevational view thereof.

Figure 7 is an enlarged detail view disclosing one end of the supporting arm forming a part of the curler.

Figure 8 is a side elevational view thereof.

Figure 9 is an elevational view of a supporting iron employed for marcelling. 55

Figure 10 is a sectional view taken on line 10-10 of Figure 7.

Figure 11 is an elevational view partly in section disclosing a supporting iron and the 60 manner of positioning the hair thereon.

Referring to the drawings in detail, the device includes a body portion 5 which is formed preferably of fiber, but it is to be understood that any suitable material may 65 be employed in the construction of the body portion.

The body portion 5 is tubular in formation and has its ends closed by disks 6 and 7 respectively, the disk 6 being provided with 70 an opening to accommodate the insulating member 7' through which the wires 8 and 9 extend, the wires being supported in a suitable tubular housing 10.

Positioned within the body portion 5 is 75 a tubular member 11 formed of asbestos material insulating the body portion against heat from the heating element of the device, so that the body portion may be conveniently handled by the operator without fear 80 of burning his hands.

A disk of asbestos material indicated at 12 closes one end of the tubular member 11 to insulate the disk 6 from the heat of the heating element within the device. A tubular member 13 formed of suitable metal is positioned in the body portion and contacts with the asbestos member 11 to support asbestos yarn indicated at 14, within the body portion. 85

Positioned in the body portion and supported in spaced relation with the member 13 is a metal tubular member 15 in which is positioned the supporting member 16 which has tapered walls and a flange 17, the flange 95 being adapted to fit within the member 15 to hold the supporting member 16 in position.

Surrounding the member 15 is a tube 18 formed of mica to support the resistance wires 19 employed for heating the interior 100

of the device, the resistance coils 19 being shown as in circuit with the wire 9 through the thermostat 20 which is shown as in its inactive position. This thermostat is of a construction such that when the temperature within the member 15 reaches a predetermined degree, the expansion of the thermostat will cause the contact arms thereof to disengage each other to break the 10 circuit.

A semi-cylindrical mica member 21 is positioned over the coil 19 and embraces the lower portion thereof so that the coil 19 may be insulated from the wire 9 which 15 extends into the body portion and has connection with the coil 19 at the outer end of the device. The asbestos yarn 14 is packed around the tubular member 18 and over the wires 19 insulating the wires from each other 20 and at the same time providing means for supporting the wires and tubular members in their proper positions.

A supporting wall is indicated at 22 and is provided with an opening to accommodate 25 the wires 8 and 9 and tubular members supporting them. The outer end of the body portion is closed by the member 23 which is formed with a finger 24 under which the movable section 25 lies when one of the 30 hair supporting irons is positioned in the device. The cut out portion 26 provides a clearance for the hair supporting members to be hereinafter more fully described to allow them to be positioned in the device.

The hair supporting devices forming a part of the invention are especially constructed for making a permanent wave and a permanent Marcel wave, the iron for accomplishing the permanent wave being indicated by the reference character 27. This iron includes a tubular body portion around which the hair to be curled may be wrapped, there being provided a plug 28 adapted to be positioned in one end of the member 27.

This plug 28 is provided with cut out portions 29 to accommodate a securing member indicated at 30 which securing member may be positioned around the hair to further twist the hair on the iron 27. The inner 50 end of the plug 28 is provided with a resilient finger 31 which will permit the plug to rotate in one direction, but restrict movement of the plug in the opposite direction. Thus it will be seen, due to this construction that when the hair has been placed on the iron and the plug rotated in one direction to further secure the hair to the iron, reverse movement of the plug will be prevented, to the end that the hair will be securely held in a twisted position.

The iron employed for Marcel waving the hair and which is illustrated by Figure 9 of the drawings, includes a pair of tubular members indicated at 32, which tubular members are supported in spaced relation

with each other by means of the member 33, which includes fingers 34 that extend into tubular members 32.

The outer ends of the tubular members 32 are held in spaced relation by means of the 70 plug 35 which is formed with extensions 36 that are positioned in the ends of the tubular member 32. In this form of the invention, when the hair is positioned thereon, the hair is woven between the tubular 75 member 32 and wrapped around the tubular member 32 in a manner as illustrated in Figure 9, thereby giving the Marcel wave to the hair.

It might be further stated that a handle 80 indicated at 37 is secured to the body portion 5 and affords means whereby the device may be held in the hands of the user, while being properly adjusted. An eye bolt 38 is secured to the body portion and provides 85 means to allow a hook of the usual supporting member employed for supporting the devices while in use, to be positioned therein.

In the use of the device, the hair to be 90 curled is wrapped around the iron to be used, and the iron is positioned in the heating chamber or tubular member 15 and the electric current is turned on.

As the current passes into the resistance 95 coil, it is obvious that the heat will pass into the tubular member 15 in which the hair is positioned. It is to be understood that prior to the positioning of the supporting iron and hair wrapped therearound, the 100 hair is treated with a suitable fluid employed in permanent waving, which fluid when heated, acts to retain the wave in the hair.

It will be seen that due to this construction, the hair under treatment is supported 105 in spaced relation with the heating element, and does not in any way contact with a heated iron which would kill the hair and cause it to fall out.

We claim:

1. In a device of the character described, a body portion, a tubular member in the body portion, a heating element surrounding the tubular member, a supporting member having an inclined wall, an iron adapted to 115 be positioned in the tubular member, said iron adapted to engage the inclined wall of the supporting member when being positioned in the tubular member to cause the iron to be supported centrally of the tubular member and in spaced relation with the walls thereof, and means for closing the ends of the tubular member.

2. In a device of the character described, a body portion, a tubular member within the 125 body portion, a heating element surrounding the tubular member, means for insulating the tubular member from the body portion, said tubular member constituting a heating chamber, a stationary member positioned at 130

one end of the body portion, a movable member associated with the stationary member and having a cut out portion, said cut out portion adapted to accommodate one end of a curling iron to support the iron in spaced relation with the tube.

In testimony that we claim the foregoing

as our own, we have hereto affixed our signatures in the presence of two witnesses.
